UNITED STATES PATENT OFFICE.

WILLIAM ROBINSON AND JOHN WILLIAM TUNSTALL, OF BOLTON, ENGLAND, AS
SIGNORS TO HARRY TUNSTALL, OF FAIRHAVEN, MASSACHUSETTS.

DIRECTION INDICATOR FOR ROAD VEHICLES.

Application filed April 22, 1925, Serial No. 24,951, and in Great Britain May 8, 1924.

Our invention relates to devices or apparatus whereby the driver of a road vehicle may indicate, both at the front and at the rear of the vehicle, the direction in which he is about to go or follow whether it is during the day or during the night or during low visibility and our said invention consists in an improved construction and arrangement of parts whereby a light may be laid bare or a moving light may be employed during dark weather or in the latter arrangement the device may be used without such light, our said apparatus being of such a character that when the light or indicator occupies a central position the straight direction ahead is indicated while the driver may move said light or indicator to the left or to the right or may lay bare such light to the left or to right to indicate the direction about to be taken and when liberated or left free said light or indicator returns to its central position.

In carrying our invention into effect we make use of devices illustrated by the accompanying drawings in which:—

Fig. 1 is a front elevation showing in full lines our improved indicator in its normal central position, while the broken lines show the same indicator in its respective positions to the right and left of said normal position.

Fig. 2 is a sectional elevation of certain parts shown by Fig. 1 and illustrates the operating parts thereof hereinafter described.

Fig. 3 is a sectional side elevation of the parts shown by Figs. 1 and 2.

Fig. 4 is an elevation of a device which we may use at the rear of a vehicle and arranged same to be brought into use in conjunction with our improved devices shown by Figs. 1 to 3.

In carrying our invention into effect we make use of an arm 2^a which is fixed upon a shaft 3 extending across a casing 4, the arm having a downwardly projecting extension 8 provided with two laterally projecting pins f and g.

The casing 4 supports the shaft 3 by bearings 3^a which are fixed upon the upper wall 3^b of the casing. Through said upper wall or cover a slot s is formed, through which the extension 8 and end portions of the springs hereinafter described extend.

Upon the shaft 3 are mounted two spiral springs 7 and 7^a and each of these springs

has one of its extending ends fixed or resting upon the bearings 3^a while the other end a or a' of the spring 7 or 7^a extends downwardly to contact with a fixed stop bar 21 against which it will press when free and thus be arrested in its normal position.

The fixing of the springs 7 and 7^a upon the shaft 3 is also such that the recoil of these springs causes the outer ends of their extensions a and a' to press against the stop bar 21 as stated, while when in this position they secure the arm 2^a in its normal central position as is shown in full lines, Fig. 1, whereas when the arm 2^a is moved to the left or to the right then one or other of the springs 7 or 7^a is put into a state of tension while the other remains inactive and in its normal position.

Fixed upon the shaft 3 is a pulley 9 around which a cord or chain 10 may be made to pass in order that the shaft 3 may be turned by having said chain or cord fixed to an operating hand lever or the like under the control of the driver who may then move such lever to turn the shaft 3 as is desired. Or in place of the pulley 9 and cord 10 any suitable lever devices may be made use of for turning the shaft 3 and its arm 2^a.

When the shaft 3 is turned as above described it carries with it the arm 2^a and consequently the extension 8 of said arm so that when moving to the left as shown by Figs. 1 and 2 the projecting pin f will have carried the extension a' of the spring 7^a into the position shown by Fig. 2, consequently the spring 7^a will be put into a state of tension so that it is adapted to cause the return of said extension 8 and pin f when the operating device is released and said end of the spring a' will return to bring its lower end into contact with the stop bar 21 thus said spring assumes its normal position.

When the shaft 3 is turned in the opposite direction then the pin g on the extension 8 will come in contact with the lower end of the extension a from the spring 7 and so will wind up said spring 7 simultaneously with the moving of the arm 2^a to the opposite side of its centre and again when liberated, said spring 7 by its recoil will bring the arm a into its normal central position.

At the upper end of the arm 2^a we mount the arrow shaped head 20 which is the indicating device and we prefer to form this

head 20 as a lamp preferably of the electric type so that by having current supplied thereto the direction indicator may be used in the dark as the shape of the lamp will indicate the position it occupies.

Current is conducted to the lamp 20 through any suitable conducting wires as will be understood.

As means for giving indication at the rear 10 of the vehicle we mount a lamp casing 4^b in a suitable position either at the rear of the vehicle or at the side thereof so that those behind the vehicle may have the direction indicated to them that the driver intends to take.

This lamp casing 4^b has in its side wall, transparent openings in the form of the letters L and R or in the form of arrows c and d as shown by Fig. 4. Or the wall may 20 be transparent while the letters and arrows are opaque so that when the arm and the lamp 20 at the front of the vehicle are moved to the left, the letter L and the arrow c will be illuminated at the rear of the vehicle; 25 whereas when the driver moves the lamp 20 to the right, then the latter R and the arrow d will be displayed by being illuminated, or we may make use of only the letters L and R or the two arrows alone in the manner 30 described.

In connection with apparatus and devices hereinbefore described we make use of terminals 10^a and 10^b which are in the form of springs as shown by Fig. 2. These terminals we arrange so that as the extension 8 is moved to the right as is shown by Fig. 2 it will complete the circuit through the spring 10^a and light up the letter L and arrow c at the rear of the vehicle, while when said extension 8 is moved to its opposite position then it couples the circuit through the spring 10^b and lights up the letter R and arrow d.

The springs 10^a and 10^b are preferably so situated that the moving of the end of the extension 8 may proceed beyond said springs 10^a and 10^b thus it completes the circuit momentarily and causes a flash of light at the rear of the vehicle and this flash would call the attention of those behind the vehicle so that the direction might be more clearly indicated. Further than this on the extension 8 returning it would again cause a flash to the rear of the vehicle which would accentu-

55 head 20 as a lamp preferably of the electric type so that by having current supplied thereto the direction indicator may be used in the dark as the shape of the lamp will indicate the position it occupies.

It will now be seen that a direction indicator embodying the invention, includes a casing having shaft bearings 3^a, and a spring stop 21, an indicating arm 2^a fixed to the shaft and projecting radially therefrom, 60 said arm having an extension 8, operating means such as the pulley 9 and cord or chain 10 for rocking the shaft in its bearings to vary the angular position of the arm, and oppositely acting springs such as 7 and 7^a 65 engaged with the casing and with the arm extension and adapted to cooperate with the stop 21 to normally hold the arm 2^a in the predetermined central position shown by full lines in Fig. 1, the arm being movable in 70 opposite directions from said position by the operating means.

It will also be seen that the arrangement is such that a movement of the arm 2^a in either direction from its central position, 75 tensions one of the springs without tensioning the other, the tensioned spring acting to return the arm 2^a to its central position when the operating means is released, and being limited in its action by the stop 21, so 80 that the two springs normally hold the arm 2^a in its central position.

We claim:

A direction indicator comprising a casing 85 having shaft bearings, an indicating member-carrying shaft journaled therein, operating means for rocking the shaft, and means for normally holding the shaft between the extremes of its rocking movement, said means including a spring stop fixed to the 90 casing, an arm fixed to the shaft, and oppositely acting springs supported by the casing and engaged with the arm, said springs co-operating with the stop and arm to manually hold the arm in a predetermined central position, and the shaft between the extremes of 95 its rocking movement, the arrangement being such that a movement of the arm in either direction from its central position tensions one of the springs, without tensioning 100 the other, the tensioned spring acting to restore the arm to its central position and being limited in its action by the stop.

JOHN WILLIAM TUNSTALL.
WILLIAM ROBINSON.
